(57) **CLAIM**

The ornamental design for a led headlight, as shown and described.

DESCRIPTION

FIG. 1-1 is a front elevational view of a led headlight showing my new design;

FIG. 1-2 is a rear elevational view of FIG. 1-1;

FIG. 1-3 is a left side elevational view of FIG. 1-1;

FIG. 1-4 is a right side elevational view of FIG. 1-1;

FIG. 1-5 is a top plan view of FIG. 1-1;

FIG. 1-6 is a bottom plan view of FIG. 1-1;

FIG. 1-7 is a perspective view of FIG. 1-1;

FIG. 1-8 is a changing status view of FIG. 1-7;

FIG. 2-1 is a front elevational view of another led headlight showing my new design;

FIG. 2-2 is a rear elevational view of FIG. 2-1;

FIG. 2-3 is a left side elevational view of FIG. 2-1;

FIG. 2-4 is a right side elevational view of FIG. 2-1;

FIG. 2-5 is a top plan view of FIG. 2-1;

FIG. 2-6 is a bottom plan view of FIG. 2-1;

FIG. 2-7 is a perspective view of FIG. 2-1; and,

FIG. 2-8 is a changing status view of FIG. 2-7.
